UNITED STATES PATENT OFFICE.

EDWARD C. BROWN, OF ROCHESTER, NEW YORK.

SPRAY-NOZZLE.

1,029,909.

Specification of Letters Patent. Patented June 18, 1912.

Application filed January 3, 1910. Serial No. 536,096.

To all whom it may concern:

Be it known that I, EDWARD C. BROWN, of Rochester, in the county of Monroe and State of New York, have invented certain new and useful Improvements in Spray-Nozzles; and I do hereby declare the following to be a full, clear, and exact description of the same, reference being had to the accompanying drawings, forming a part of this specification, and to the reference-numerals marked thereon.

My present invention relates to spray nozzles, and it has for its object to provide a simple, cheap and durable device of this character all parts of which will be readily and quickly accessible for cleaning and other purposes.

A further object of my invention is to construct a nozzle in which both the quantity and nature of the stream can be regulated, the controlling devices therefor being well protected within the interior of the nozzle, and on the whole the invention is directed toward the provision of an article which will be especially adapted in the before-mentioned and in other ways to use in connection with the spraying of plants and flowers.

To these and other ends the invention consists in certain improvements and combinations of parts all as will be hereinafter more fully described, the novel features being pointed out in the claims at the end of the specification.

In the drawings: Figure 1 is a side elevation, partly in section, of a nozzle constructed in accordance with and illustrating one embodiment of my invention, the section being taken substantially on the line 1—1 of Fig. 3; Fig. 2 is a longitudinal section taken substantially on the line 2—2 of Fig. 3; Fig. 3 is a top plan view of the parts with the outer cap removed; Fig. 4 is a bottom plan view of the inner cap; Fig. 5 is a bottom plan view, partly in section, of a modification illustrating a different method of arranging the screen, and Fig. 6 is a section of the modified device taken substantially on the line 6—6 of Fig. 5.

Similar reference numerals throughout the views indicate the same parts.

The nozzle constituting the present embodiment of my invention comprises generally three parts, namely, a body portion or casting 1, an inner cap 2 and an outer cap 3, all of these parts being preferably threaded

together so that they may be conveniently separated as occasion requires. The body portion 1 includes a supply passage 4, the outer end 5 of which is threaded to form a means of attaching the connecting nipple of a supply pipe (not shown) while the upper expanding portion is formed with an inner ledge or shoulder 6, upon which is seated a suitable wire or other screen 7. This screen is held in place against its seat by the engaging pressure of the inner flange or end 8 of the inner cap 2, which latter and the body portion are preferably provided externally with coöperating flanges 9 and 10 that receive between them a suitable compressible gasket 11. The cap 2 is threaded into the body portion 1 into engagement with the screen, at the same time compressing the gasket and producing a liquid tight joint.

On the outwardly projecting portion 12 of the inner cap 2 is threaded the before-mentioned outer cap 3 that forms together therewith an annular chamber 13 and the outer wall 14 thereof is provided with a discharge orifice 15 (Fig. 1), arranged concentrically with respect to the chamber. This outer wall may be formed integrally with the cap, but in order to simplify the construction somewhat I prefer to form it of an independent plate which is held between the shoulder 15^a of the cap and the adjacent end of the inner cap 2, a gasket 16, similar to the first being preferably interposed to seal the joint, and also, in the present instance, to constitute a spacing member that defines one dimension of the chamber. This wall or plate can be formed of sheet metal, and I prefer to stamp or press an annular rib 17 therein to increase the capacity of the chamber at its circumference for purposes that will later appear.

In the outer wall 18 of the inner cap 2 is formed near the circumference of the chamber a diagonal passage 19 leading from what may be termed the pressure chamber 20, within the inner cap, to the mixing chamber 13 between the inner and outer caps, and it is so arranged as to intersect the latter chamber substantially tangentially thereof. One wall of the passage is extended to project within the chamber 13 in the form of a diagonally disposed hood or plate 22 to direct the stream in this tangential direction while another portion of the passage wall is similarly projected as at 23 within

the chamber 20, and these two walls are rendered adjustable relatively to each other substantially in the plane of the outer wall 18 of the inner cap to enlarge or restrict the flow through the passage, as desired. 5 I accomplish this adjustment in the present instance by pivoting, preferably centrally at 24, on the inner or under side of the wall 18, a segmental plate 25, best shown in Fig. 4, that is rotated by means of a finger piece 26. This plate carries the wall 23 of the passage forming, in effect, a section thereof and by rotating it in one direction the latter can be gradually restricted and finally 15 closed entirely, the plate having sufficient frictional resistance against the wall on which it is mounted to hold its various positions of adjustment. In closing this diagonal intake passage the plate may be 20 also manipulated to a position in which it simultaneously opens a direct passage 27 through the wall 18 that extends in substantially the same direction as the discharge orifice 15 in the wall 14 of the outer 25 cap.

Passing now to the operation of the device, the fluid being introduced under pressure at the point of supply 4, first passes through the screen 7, which latter intercepts any solid matter that it may carry 30 and prevents the same from reaching the more delicate parts of the apparatus, where it might lodge either in the passage 19 or in the discharge orifice. It being assumed 35 that the latter passage is open and the passage 27 closed, the liquid is introduced into the mixing chamber 13 in an oblique direction at the circumference thereof, producing a whirling motion of great velocity within 40 the chamber, the enlargement of the chamber through the provision of the rib 17 in the wall 14 contributing to this result by increasing the mass and hence the momentum at the outer circumference. The liquid, 45 however, is of necessity being forced out at the same time through the concentric discharge orifice 15, but retains to a sufficient measure its rotative force, so that it emerges in the form of a whirling spray. If, however, 50 a direct stream is required, this tangential impact of the liquid within the chamber 21 is destroyed by closing the passage 19, and opening the direct passage 27 by turning the plate 25 to the position 55 shown in Fig. 4 in dotted lines, whereat a direct outward pressure only is communicated at the discharge orifice. To make these changes of adjustment it is only necessary to remove the cap 2, the periphery of 60 which is preferably milled, from the body portion 1 whereat the operating projection 26 on the plate 25 is rendered immediately accessible.

In the uses to which the device is, as at 65 present advised, best adapted, it is not often

required that the change of adjustment be made, and with the arrangement set forth the controlling device is so situated interiorly that any inadvertent changes in the adjustment thereof due to the careless manipulation of the nozzle are not liable to take place. Neither is this device so liable to clog as one in which the means for controlling the passage works in conjunction with the discharge orifice itself. 70

In Figs. 5 and 6 I have suggested another manner in which the screen may be associated in a nozzle of different design. Therein the supply is entered through a passage *a* having a shoulder *b* against 80 which a cup shaped screen *c* is situated. The passage *a* is restricted as at *d* to discharge tangentially directly into a chamber *e* and thence out of the discharge orifice *f*. In this device no means is shown for regulating the discharge. 85

I claim as my invention:

1. In a spray nozzle, the combination with an annular chamber having a concentric discharge orifice in one wall thereof and an intake passage in the opposite wall, a portion of a wall of said passage being extended to project within the chamber at an angle to direct the flow therethrough substantially at a tangent to the chamber, of a closure for the passage, the said closure and chamber wall being relatively movable to increase or diminish the flow through the passage. 90

2. In a spray nozzle, the combination with an annular chamber having a concentric discharge orifice in one wall thereof, a direct intake passage extending in substantially the same direction as the first in the opposite wall and a second intake passage in the latter, a portion of a wall of which is extended to project within the chamber at an angle to direct the flow therethrough substantially at a tangent to the chamber, of a closure for both passages, the said closure and chamber wall being relatively movable to increase or diminish the flow through either passage, selectively. 100

3. A spray nozzle comprising an annular chamber having a concentric discharge orifice in one wall thereof, and a tangentially arranged intake passage extending obliquely through the opposite wall, the walls of said passage being relatively adjustable in the plane of the wall of the chamber to increase or diminish the flow therethrough. 115

4. The combination with a spray nozzle comprising an annular chamber having a concentric discharge orifice in one wall thereof and a tangentially arranged intake passage extending obliquely through the opposite wall, of a closure for said passage pivotally mounted on said last mentioned wall. 125

5. In a spray nozzle, the combination with a body member having a supply passage 130

entering the same and provided with an inner flange or shoulder, of a screen seated on the flange, a cap threaded into the body member and exerting pressure against the 5 margin of the screen to hold it on its seat, the outer wall of the cap being provided with a diagonal passage, and a second cap having a threaded engagement with the first to form therewith an annular chamber, 0 the outer wall of said second cap having a discharge orifice concentric to the chamber and the passage in the corresponding wall of the first being arranged to enter the chamber at a tangent.

5. 6. In a spray nozzle, the combination with a body member having a supply passage en-

tering the same, of a cap having a threaded engagement therewith and provided with a diagonal passage in its outer wall, an adjustable closure for said passage mounted on 20 the latter wall to control the flow therethrough, and a second cap having a threaded engagement with the first to form therewith an annular chamber, the outer wall of 25 said second cap having a discharge orifice concentric to the chamber and the passage in the corresponding wall of the first being arranged to enter the chamber at a tangent.
